UNITED STATES PATENT OFFICE.

JOHN COOPER WHITESIDE, OF RUTHERFORD, NEW JERSEY, ASSIGNOR TO HODGMAN RUBBER CO., OF YONKERS, NEW YORK, A CORPORATION OF NEW YORK.

CONVERTIBLE COAT AND CAPE.

1,239,995.

Specification of Letters Patent. Patented Sept. 11, 1917.

Application filed February 10, 1917. Serial No. 147,756.

To all whom it may concern:

Be it known that I, JOHN COOPER WHITESIDE, a citizen of the United States, and a resident of Rutherford, in the county of Bergen and State of New Jersey, have invented a new and Improved Convertible Coat and Cape, of which the following is a full, clear, and exact description.

The invention relates to wearing apparel and its object is to provide a new and improved convertible coat and cape more especially designed for the use of letter carriers, messengers and other persons delivering mail, merchandise and like matter and arranged to protect the carrier's sack or bag against rain, snow, dust and the like, and at the same time leaving one arm of the wearer free to permit convenient removal of the contents of the bag.

Another object is to allow the wearer to conveniently and quickly detach the cape from the garment to allow wearing the coat like an ordinary walking or street coat.

In order to accomplish the desired result use is made of a half cape and fastening means for detachably fastening the half cape to a coat.

A practical embodiment of the invention is represented in the accompanying drawings forming a part of this specification, in which similar characters of reference indicate corresponding parts in all the views.

Figure 1 is a front perspective view of the convertible coat and cape as applied;

Fig. 2 is a similar view of the coat as applied and with the cape removed;

Fig. 3 is a rear perspective view of the convertible coat and cape as applied;

Fig. 4 is an inverted plan view of the half cape;

Fig. 5 is a rear elevation of the upper portion of the coat; and

Fig. 6 is an enlarged transverse section of the coat and cape on the line 6—6 of Fig. 3.

The body 10 of the coat is provided with a collar 11 and sleeves 12 and the coat is open along the front median line to form flaps 13 and 14 adapted to be fastened together in overlapping relation by the use of

fastening devices of any approved construction, preferably, however, fastening devices in the form of buckles each having a slotted member 16 fixed to the flap 14 and a member 15 fixed to the flap 13 and provided with a

spring-pressed retaining arm or lever 17 pivoted on the member 15 and adapted to

engage the slotted member 16, as will be readily understood by reference to Figs. 1 and 2. A half cape 20 is adapted to be removably attached to the coat to hang over one shoulder and the corresponding sleeve 12, preferably the left shoulder and the left sleeve, as shown in Figs. 1 and 3. The body of the half cape 20 is in the form of a quadrant and slightly in excess thereof, as plainly shown in Fig. 4, and the half cape is provided with a neckband 21 having on its under side fastening members 22 adapted to engage fastening members 23 (see Fig. 5) attached exteriorly to the left-hand side of the neckband of the collar 11. The half cape 20 is provided along its back margin 24 with fastening members 25 adapted to engage the fastening members 26 arranged externally on the body 10 of the coat along the median back line thereof, as plainly indicated in Fig. 5. The fastening members 22, 23 and 25, 26 are preferably of the socket and stud type to permit of readily connecting the members with each other or disconnecting the same when it is desired to remove the half cape from the coat.

The front margin 27 of the half cape 20 is provided with fastening members 28 preferably similar to the members 16 above referred to, and the said fastening members 28 are spaced relatively to the arms 17 to be engaged by the latter at the time the arms 17 engage the fastening members 15 so that no extra fastening members on the coat body 10 are required for fastening the front of the half cape 20 to the front of the coat body 10.

It will be noticed that the half cape 20 can be readily attached to the neckband of the collar 11 and at the back of the coat so that the half cape overlies the left shoulder and arm of the wearer to effectively protect a bag or a sack suspended in the usual manner from the left shoulder of the wearer.

It will also be noticed that the turndown portion of the collar 11 completely covers up the fastening devices 22, 23, and, if desired, the front of the half cape may be closed by engaging the arms 17 with the fastening members 28. When the cape is in use, the right arm of the wearer is completely free and unobstructed or unhampered by the cape and hence a mail carrier or other person can readily use the right hand for removing letters or other contents from the bag or sack and delivering the same

to the proper parties. The half cape 20 can be quickly detached from the coat, then folded up and placed in the sack or bag or into a pocket of the coat, if desired. The 5 coat is then worn like an ordinary walking or street coat, as will be readily understood by reference to Fig. 2.

The coat and the half cape are preferably made of waterproof material. By providing 10 the half cape instead of a full cape the wearer has less weight to carry besides having the freedom of one arm and hand, as above explained.

Having thus described my invention, I 15 claim as new and desire to secure by Letters Patent:

1. A garment, comprising a coat, a half cape covering one shoulder and sleeve and extending from the front median line to the 20 back median line of the coat and fastening means detachably fastening the said half cape to the said coat along said median lines.

2. A garment, comprising a coat, a half

cape, a set of fastening members arranged exteriorly on one side of the coat collar and 25 along the median back line of the coat, and a set of fastening members arranged on the under side of the half cape along the collar and along the margin of the rear edge of the half cape, the said half cape fastening members being adapted to be engaged with the said coat fastening members to hold the half cape removably in position on the coat.

3. A garment, comprising a coat provided at its open front with fastening members to 30 close the coat front, a half cape, fastening members arranged along the front of the half cape and adapted to coat with the said coat front fastening members to attach the front of the half cape to the front of the 40 coat, coacting fastening members extending along one-half of the coat collar and along the cape collar, and coacting fastening members extending along the back median line of the coat and the back of the cape.

JOHN COOPER WHITESIDE.
